UNITED STATES PATENT OFFICE.

ELBRIDGE J. STEELE, OF NEW HAVEN, CONNECTICUT, ASSIGNOR TO
SARGENT & CO., OF SAME PLACE.

DESIGN FOR A TWINE-HOLDER.

Specification forming part of Design No. 6,276, dated November 26, 1872.

To all whom it may concern:

Be it known that I, ELBRIDGE J. STEELE, of New Haven, in the county of New Haven and State of Connecticut, have invented a new Design for Twine-Holder; and I do hereby declare the following, when taken in connection with the accompanying photographic illustration, to be a full, clear, and exact description of the same, and which said illustration constitutes part of this specification and represents a perspective view.

This invention relates to a design for what is known to the trade as a twine-holder; and consists in the peculiar configuration of the parts, as more fully hereinafter described.

The case consists of an upper and lower part, the division being horizontal and near the center, and each part formed of open tracery and ornamented, as shown in the accompanying

illustration. The base is supported upon feet, each representing a leaf and with ornamentation and tracery, as shown in the illustration. The case is attached centrally upon the base, but both are made independent each of the other; therefore a different base may be substituted for this case or a different case for the same base. Hence I do not confine my design to the combination of the case and base, but to either part, whether used separately or together.

I claim as my invention—

The design for twine-holder, as herein described and shown in the accompanying illustration.

ELBRIDGE J. STEELE.
